UNITED STATES PATENT OFFICE.

WALTER H. KAUL, OF MEXIA, TEXAS.

METHOD OF TREATING OIL.

Application filed January 25, 1922. Serial No. 531,690.

To all whom it may concern:

Be it known that I, WALTER H. KAUL, a citizen of the United States, residing at Mexia, in the county of Limestone and State 5 of Texas, have invented certain new and useful Improvements in Methods of Treating Oil, of which the following is a specification.

This invention relates to the treatment of 10 oil and more particularly to the treatment of crude oil or petroleum to separate water therefrom.

The invention has for its main object the provision of an improved method of treating 15 crude oil or petroleum prior to the distillation thereof whereby the oil is thoroughly, efficiently and economically dehydrated.

Another object relates to the dehydrating of such crude oil in a continuous manner so that the movement of the crude oil through the treating apparatus and into the still may take place without interruption.

Another feature of the invention relates to the employment of molasses as the dehydrating agent, which material is relatively cheap and easily obtainable in districts near many of the producing oil fields.

Other objects will appear from the following description of the invention taken in connection with the drawing, in which the figure is a diagrammatic view showing one form of apparatus suitable for carrying out my process.

Certain kinds of crude oil, particularly those produced in the Gulf States and known as "roily" oils, are mixed with a relatively high percentage of water in a more or less emulsified state, and it is exceedingly difficult and expensive to separate this water 40 from the oil in order to render the oil commercially valuable. Permitting the mixture to stand or merely boiling it in the usual manner even for extended periods has little or no effect, while the only effective method 45 of separation which has been developed, so far as I am aware, necessitates the use of relatively large quantities of an expensive chemical which of course adds to the final cost.

On the other hand, I have found that by introducing relatively small quantities of a comparatively cheap and readily obtainable

substance, such as molasses, having a high affinity for the water in the mixture, prior to the heating of the same, I am enabled to 55 secure substantially complete separation of the oil and water, thereby effecting a great saving over the said prior process.

Referring to the said drawing, the crude oil is led from a tank 1, which is preferably 60 formed of sheet metal plates suitably riveted or welded together to be liquid tight by means of a pipe 2 provided with a controlling valve 3 to the suction side of a steam or other pump 4. Means are provided for injecting into the said pipe 2 a supply of dehydrating agent, comprising an inlet pipe 5 leading from a storage tank or reservoir 6 containing molasses, glucose, glycerine, or other suitable substance possessing a relatively 65 high affinity for water, and having a specific gravity greater than water. A valve 7 controls the supply of the said dehydrating agent.

Leading from the discharge side of the 75 pump 4 is a pipe 8 controlled by a valve 9, and provided at 10 with a suitable reducing connection adapted to produce an intimate mixture of the molasses or other dehydrating agent, with the emulsified oil and water. A 80 smaller pipe 11 leads from the said reducer 10 to the interior of the first of a series of heater heads 12, which comprise sections of pipe suitably closed at their ends and connected together as by the connections 13. 85 Suitable heating elements, such for example, as the steam pipes 14 pass through one of the closed ends of each of the said heads 12, and are adapted to control the temperature within the said heads.

The last of the said heads 12 is connected with a second tank 15 preferably formed of steel plates suitably riveted or welded together to be liquid tight and having positioned therein a heater element 16 for heating the contents of the tank. Mounted in the tank 15 is a filter element comprising a mass of excelsior 17 suitably retained in position as for example, by means of a pair of perforated members 18 secured to the 100 walls of the tank. An outlet 19 is provided for discharging the oil, the viscosity of which is such as to permit it to pass through the filter. Leading from a lower portion of

the tank 15 below the filter and controlled by a valve 20 is a water outlet pipe 21 which may empty into a waste pipe or any convenient sewer. Substantially all of the molasses and water is stopped by the filter 17 and is collected in the lower portion of the tank 15, from which it is drawn off through the said pipe 21 and discharged into the said sewer.

10 The pipe 19 leads from the said tank 15 either to the distilling apparatus direct, or to an intermediate storage tank 24, as may be desired. As shown, an intermediate tank is provided, which may be made of 5 steel plates or the like, suitably welded or riveted together to be liquid tight. From a lower portion of the tank 24, a discharge pipe 25, controlled by a valve 26, leads into any convenient waste pipe or sewer, while 10 from an upper portion of the tank 24 a pipe 27, controlled by a valve 28, leads to the distilling apparatus of an oil refinery.

15 The levels of the respective tanks are preferably so adjusted that the contents of 25 the tank 1 discharges to the pump 4 by gravity, and the upper portion of the tank 15 discharges into the tank 24 by gravity, while the tank 24 discharges through the pipe 27 into the still by gravity.

20 In operation, the roily crude oil is led from the tank 1 through the pipe 2 to the suction side of the pump 4, and molasses of the kind known as black strap is supplied thereto through the pipe 5. The valves 3 25 and 7 may be employed for properly proportioning the quantity of molasses or other dehydrating agent relative to the quantity of the oil. From the said pump the mixture is forced through the pipe 8 past the reducer 10 and into the heating heads 12 where its temperature is raised by means of the heater elements 14. Molasses, glucose, glycerine, and the like, possess a strong affinity for water and have substantially no affinity for 45 oil, so that when the mixture is introduced into the tank 15 by means of the connecting passage 30, the molasses or other agent has absorbed and carries with it substantially all the water which was contained in the 50 crude oil. Heat is applied to the contents of the tank 15 by means of the heater element 16. The filter formed of the excelsior 17 clarifies the mixture by holding back the mixture of molasses and water, while the oil 55 passes through the said filter and is discharged out of the pipe 19 into the storage tank 24. Here any water that was carried out through the passage 19 by incomplete separation in the tank 15 will settle to the bottom, due to the fact that the specific 60 gravity of the water has been raised by its mixture with the molasses, and may be drawn off through the discharge outlet 25. The oil having a relatively lower specific 65 gravity remains on top and is drawn off

separately through the pipe 27. The relative proportions of the molasses and oil will vary somewhat, depending upon the amount of water contained in the roily oil, and its state of emulsification, which may be readily determined by an experienced oil man. However, an example of the relative proportions actually employed in one instance, where the oil was not badly off color due to emulsified water and other impurities, was 70 from six to seven gallons of molasses to each thousand barrels of oil. This produced an oil containing less than two per cent of water; but it will be understood that these proportions must be varied to suit different 75 kinds of oil, increasing the quantity of molasses as the quantity of emulsified water and other impurities contained in the oil increases.

80 The heat supplied by the heating pipes 14, and the coil 16, may ordinarily be within the limits obtainable by steam at atmospheric pressure; however, in extreme cases, super-heated steam may be employed for raising the temperature to say 350 degrees F. 85

90 Since the black strap molasses is an exceedingly viscous liquid, in some instances it may be desirable to thin it somewhat before introducing it into the oil mixture, and this may be accomplished by merely adding 95 water thereto while it is in the storage chamber or reservoir 6. Good results have been obtained when employing molasses which has been thinned in the proportions of say 45 gallons of molasses and 100 barrels of water.

100 Apparatus of preferred form and construction has been illustrated and the preferred steps constituting the method described for the purpose of showing a way 105 in which this invention may be practiced, but the inventive thought upon which this application is based is broader than this illustrative embodiment. It is therefore understood that the scope of the invention is not to be limited by the above disclosure, reference being had to the appended claims for that purpose.

Having thus described this invention, what is claimed is:

1. The method of treating crude oil which comprises bringing the crude oil into intimate contact with molasses; and separating the oil from the remaining parts of the mixture prior to distillation.

2. The method of dehydrating crude oil which consists of bringing molasses into intimate contact therewith, applying heat to the mixture, filtering the mixture, and settling the molasses and water out of the mixture.

3. The method of dehydrating roily oil which consists of applying molasses thereto under heat, and filtering the mixture.

4. The method of dehydrating roily oil

which consists of applying molasses thereto under heat, and filtering and settling out foreign substances from the oil.

5. The method of dehydrating oily crude oil which consists in intimately mechanically mixing molasses with said oil; raising the temperature of said mixture; filtering the mixture while maintaining it at said

elevated temperature to separate said oil from said molasses and water; and settling 10 the filtrate, to separate any molasses and water which may have passed through the filter.

In testimony whereof I affix my signature.

WALTER H. KAUL.
